US00D477354S

(12) United States Design Patent (10) Patent No.: US D477,354 S
Leu (45) Date of Patent: * Jul. 15, 2003

(54) TYPE FONT

D324,535 S * 3/1992 Stone D18/24
D429,274 S * 8/2000 Kobayashi D18/24

(75) Inventor: Olaf Leu, Wiesbaden (DE)

(73) Assignee: Heidelberger Druckmaschinen AG,
Heidelberg (DE)

() Term: 14 Years

(21) Appl. No.: 29/150,555

(22) Filed: Nov. 14, 2001

(30) Foreign Application Priority Data

May 16, 2001 (DE) 4 01 50 007

(51) LOC (7) Cl. 18-03

(52) U.S. Cl. D18/24

(58) Field of Search D18/24-33; 101/398,
101/399
